Atty's.

UNITED STATES PATENT OFFICE

PAUL A. HENTSCHEL, OF BALTIMORE, MARYLAND, ASSIGNOR TO VENTFLECTOR COMPANY, INCORPORATED, OF BALTIMORE, MARYLAND, A CORPORATION OF MARYLAND

DEFLECTOR FOR GAS STOVES

Application filed August 25, 1931. Serial No. 559,293.

The invention relates to deflectors for use on gas stoves for deflecting fumes so that they will not impinge against the wall of the kitchen, or directly against the top of the stove. The invention is shown in the accompanying drawing, in which

Figure 1 is a front view.

Fig. 2 is a vertical section from front to rear.

Fig. 3 is a vertical sectional view from side to side of the appliance.

Fig. 4 is a bottom plan view.

In this drawing 1 is the chimney to be mounted on the collar of the stove, said chimney being of elongated cross sectional form with rounded ends. The rear wall of the chimney extends above the level of the top edge of the front wall, and to this rear wall extension a hood is secured composed of a rear wall substantially in the vertical plane of the rear wall of the chimney, said walls being secured together by rivets, or other suitable fastenings, a top wall 2 which inclines upwardly and forwardly, end walls 3, which incline outwardly and forwardly, and bottom wall portions 4 which incline downwardly and forwardly. These latter wall portions are formed to fit the curved ends of the chimney, and they fill the spaces between the end walls of the hood and the curved end wall portions of the chimney. By this construction the only outlet for the fumes emanating from the gas stove is at the front of the hood, and it will be noticed that the hood is of elongated form in respect to the long dimension of the chimney, so that said hood reaches considerably beyond the curved end walls of said chimney.

By reason of the flaring construction of the hood, that is, increasing in volumetric capacity towards the front, a free discharge of the fumes from the gas stove is provided for not only directly in line with the chimney, but out beyond the chimney at both sides thereof, and this discharge takes place in a forward direction only so that the fumes are directed away from the walls of the kitchen, and are not directed downwardly towards the top of the stove.

There is a grille plate 5 extending over the

open front of the hood, said grille plate preferably being formed of cast metal, though the invention is not limited in this respect. The grille is made up of bar portions connecting with each other, and other bar portions which extend into the spaces, and have free terminal end portions. This grille plate is secured to the hood by ears 6 on the hood bent into engagement with the end edges of the grille plate. The grille plate is also secured to the front wall of the chimney by a rivet at 7.

I claim:

1. A deflector for the fumes of gas stoves comprising a chimney portion to fit the collar of the gas stove, a hood attached to said chimney, said hood being of elongated form and reaching beyond the opposite sides of the chimney portion, said hood being made up of a top, back and end walls, together with bottom wall portions between the said end walls and the adjacent sides of the chimney, the discharge opening from said hood being only at the front thereof, substantially in the same vertical plane with a front wall portion of the chimney, the rear wall of the hood being substantially in the same vertical plane with a rear wall portion of the chimney.

2. A deflector according to claim 1 in which the top wall of the hood extends upwardly and forwardly at an inclination.

3. A deflector according to claim 1 in which the end walls of the hood incline outwardly from rear to front.

4. A deflector according to claim 1 in which the top and bottom walls of the hood diverge forwardly and the end wall diverges forwardly.

5. A deflector according to claim 1 in which the front opening is provided with grille work.

6. A flue pipe of elongated cross sectional form with rounded ends, and with the rear wall extending upwardly into a higher plane than the front wall, a hood having a back wall attached to the upward extension of the pipe rear wall and substantially in the same vertical plane therewith, said hood having top and bottom walls diverging forward.

ly in respect to each other, and ends walls also diverging forwardly in respect to each other, the bottom wall extending from the end walls to the curved ends of the pipe and a grille at the front opening of the hood, attached to said hood and to the front wall of the pipe, substantially as described.

In testimony whereof, I affix my signature.
PAUL A. HENTSCHEL.
